Primary Examiner—A. Hugo Word*Assistant Examiner*—Cathy Anne MacCormac*Attorney, Agent, or Firm*—Thomas E. Schatzel**[57]****CLAIM**

The ornamental design for a recuperative animal support harness, as shown and described.

DESCRIPTION

FIG. 1 is a perspective view of a recuperative animal support harness showing my new design, the broken line showing of a dog is for illustrative purposes only and forms no part of the claimed design;

FIG. 2 is a top plan view thereof;

FIG. 3 is a bottom plan view thereof;

FIG. 4 is a right side elevational view, the left side being a mirror image of the right side shown;

FIG. 5 is a front elevational view; and,

FIG. 6 is a rear elevational view.

The strap in FIGS. 1-6 is broken away to show indeterminate length.
